UNITED STATES PATENT OFFICE.

PAUL BAUR AND ROBERT E. LAUCK, OF TAYLOR, TEXAS.

AUTOMATIC CONTROL FOR HOT-WATER INCUBATORS.

Application filed July 6, 1922. Serial No. 573,209.

To all whom it may concern:

Be it known that we, PAUL BAUR and ROBERT E. LAUCK, citizens of the United States, and residents of Taylor, in the 5 county of Williamson and State of Texas, have invented certain new and useful Improvements in Automatic Controls for Hot-Water Incubators, of which the following is a specification.

10 It is well known to those experienced in the operation of incubators that the proper temperature during the period of incubation is approximately 103 degrees F. In incubators heated by hot air any variation from 15 this temperature is quickly controlled, but where hot water is employed as the heating medium it requires longer to either bring up or reduce the temperature. As a temperature higher than 103 degrees F. often incurs tre- 20 mendous losses in eggs and chicks more so than a slight fall of temperature, it is of great importance that means be employed to lower any increase in the temperature as soon as possible as well as to check any fur- 25 ther rise. This means usually consists of a thermostat which by its expanding action acts on certain damper levers and by lifting a damper permits the heat from the lamp to escape into the outer air. But hot water 30 holds heat very long, and furthermore water that has become overheated has risen into the upper coils in the incubator, and is therefore not affected by the lifting of the damper which only acts to check the heat- 35 ing of an additional supply of water. Our invention relates to a method of quickly reducing the temperature of the water in the coils within the machine, thereby reducing very quickly the temperature of the egg 40 chamber, this means acting in unison with the damper and controlled by the same ther- mostat. It can be applied to practically any make of hot water incubator, but is shown and described as attached to a type 45 having a hinged top.

In the accompanying drawing:

Figure 1 is a side elevation of an incubator, embodying our invention.

Figure 2 is a sectional view through the 50 incubator on the line 2—2 of Figure 1.

Figure 3 is a sectional detail view showing the connection between the thermostat and the operating mechanism for the damper and our device.

55 Figure 4 illustrates a sectional view

through the auxiliary water tank on the line 4—4 of Figure 2.

In these views 1 designates the side of an incubator to which is attached the usual lamp or other suitable water heating device 60 2. A heating coil 3 is arranged in any desired manner within the incubator, receiving hot water from the heating device 2 and returning the cooled water thereto in the usual manner. A hinged top 4 is provided 65 for the incubator. Within the incubator is placed the usual water thermostat 5 which acts upon a rod 6. A damper 7 is suspended over the lamp and is connected to one end of a lever 8 the opposite end of 70 which is acted on by the rod 6. All of the above parts are in common use in hot water incubators in one form or another. To these parts we add the following:

On the top of the incubator and back of the hinged portion 4 we place a reservoir 9 having a filling vent 10 and a gauge 11. On the side of the incubator and below the level of the reservoir is placed a water tank 12. A feed pipe 13 leads from the reservoir to 75 the tank and its lower end is slotted as at 13^a whereby water is automatically maintained in the tank at a predetermined level. A pipe 14 leads from the tank 12 and connects with any desired portion of the water 80 coils within the incubator, depending on the type of heating coil used.

A lever 15, similar to the lever 8 is pivotally mounted on the side of the incubator and extends in the opposite direction from 85 the lever 8. One end of this lever is also in engagement with the rod 6, and the other end carries a link and a slidable rod 16, working through a guide bracket 17 and supporting a ball valve 18 adapted to close 90 the upper end of the pipe 14, which extends into and approximately midway the height of the water tank 12. A coil spring 19 encircles the rod 16, and normally holds the ball valve seated.

100 As long as the temperature is normal or is below the limit set, the ball 18 remains in closed position, but when the temperature of the egg chamber rises above the predetermined limit the expansion of the thermostat will lift the damper 7 and at the same time lever 15 will be actuated in unison with the damper lever 8. This movement of lever 15 will lift the ball 18 from its seat against the tension of the coil spring 19 and cool 105 110

water from tank 12 will be admitted to the heating coil 3 of the incubator.

As soon as the temperature of the incubator drops to the required limit the contraction of the thermostat will permit the spring 19 to reseat the ball 18 and the supply of cold water will be cut off, until the temperature again rises above normal. As water is thus drawn from tank 12 in small amounts 10 it is automatically replaced by an additional supply from the reservoir 9.

It may also be remarked that in the actual running of an incubator the damper is not usually either lowered to produce a tight fit 15 over the lamp flue or lifted high above it, but usually occupies an intermediate position. The spring 19 allows for this variation, that is, a greater amount of expansion may be required in the thermostat to lift 20 the ball 19 than is required to lift the damper slightly clear of the flue, and the ball will reseat in advance of the damper.

We have not shown any overflow outlet as this is common to all types of hot water systems in use, with incubators so far as they have come to our knowledge, and is not a part of our invention. Our device is designed to be used in connection with several different forms of hot water heating and for 30 several makes of incubators, and in applying the same it is placed on the side opposite the overflow, hence the same would not appear in the present drawings.

What we claim is:—

35 1. In the combination of an incubator hav-

ing a hatching chamber, tubes for heating the chamber, a main water supply tank, and a thermostatic control, of an automatic water feeding device, comprising a stationary auxiliary water tank, a rigid supply pipe extending from the main tank to the auxiliary tank for maintaining the water in said auxiliary tank to a predetermined level, a pipe fixed to and extended through the auxiliary water tank slightly below said predetermined level, and a loosely mounted and thermostatically controlled valve for permitting water from the auxiliary tank to enter the heating tubes within said hatching chamber. 40

2. In an incubator, the combination with a hatching chamber, tubes for heating the chamber, a main water supply tank, and a thermostatic control, of an automatic water feeding device, comprising an auxiliary water tank secured to the upper edge of the incubator, a rigid supply pipe extending from the main tank to the auxiliary tank for maintaining the water in said auxiliary tank to a predetermined level, a hand operated valve carried by said supply pipe, a pipe connected with the said heating tubes at one end and extended through the auxiliary water tank at its opposite end to a point slightly below said water level, and a valve operated by the thermostat for opening and closing the last named pipe. 50

In testimony whereof we affix our signatures.

PAUL BAUR.
ROBERT E. LAUCK.
